US00D949199S

(12) **United States Design Patent** (10) **Patent No.:** **US D949,199 S**
Friedel (45) **Date of Patent:** **** Apr. 19, 2022**

(54) **ELECTRONIC DEVICE WITH ICON**

(71) Applicant: **Crestron Electronics, Inc.**, Rockleigh, NJ (US)

(72) Inventor: **William Friedel**, Yorktown Heights, NY (US)

(73) Assignee: **Crestron Electronics, Inc.**, Rockleigh, NJ (US)

(**) Term: **15 Years**

(21) Appl. No.: **29/768,261**

(22) Filed: **Jan. 28, 2021**

(51) **LOC (13) Cl.** **14-04**

(52) **U.S. Cl.**

USPC **D14/491**

(57) **CLAIM**

The ornamental design for an electronic device with icon, as shown and described.

DESCRIPTION

FIG. 1 is a front view of a first embodiment of an electronic device with icon; and,

FIG. 2 is a second embodiment thereof.

The broken lines showing the electronic device in FIG. 1 and an alternate electronic device in FIG. 2 forms no part of the claimed design. The remaining broken lines showing portions of the icon form no part of the claimed design.

1 Claim, 2 Drawing Sheets
